UNITED STATES PATENT OFFICE

KEMPTON ARTHUR EVELETH, OF PORTLAND, MAINE

COMBINATION PIPE AND LIGHTER

Application filed March 16, 1929. Serial No. 347,635.

My invention relates to smoking pipes and particularly to a combined pipe and lighter. There are many occasions on which the smoker is either disappointed for lack of a match or of the owner of a so-called automatic lighter for lack of ability to light his pipe, as for example, in wind or draft. Furthermore, the annoyance of plural smoking necessities results frequently in misplacement of 10 ignition means or at best in the collection of these various items from various pockets.

My concept analyzes the main problem as the pipe and a multiple lighter, preferably of so-called automatic type. Such lighters 15 have become what may be called a habit-necessity. While well adapted to the uses of the cigarette smoker, they are not in themselves as at present constituted well adapted to the needs of the pipe smoker because of 20 the delay between ignition and application of the flame to the filled bowl.

This delay due to the motion of application following the motion of ignition has two main difficulties. One is that of possible or probable extinguishment, and the other is that of the waste of fuel. My invention avoids these difficulties by its combination with the pipe and the pipe bowl so that the lighter is not only a part of the pipe, 25 but its igniting function takes place at the very brim of the bowl so that the first flash of the flame falls on the surface of the tobacco fill.

My invention may be best understood by 30 reference to an embodiment and I therefore have shown in the accompanying drawings an embodiment which illustrates both general principle and also a convenient and practical embodiment. In the drawings:

Fig. 1 is a view illustrative of the lighting of a pipe in accordance with my invention.

Fig. 2 is a section of such a pipe.

Fig. 3 a plan view, and

Fig. 4 an end view.

Referring to the drawings I have indicated at 1 a pipe bowl having preferably a so-called "poker" base 1¹ in which I provide a pocket or bore 4.

Adjacent the brim of the bowl 1 I locate

an ignition member 3. As shown this is a so-called flint set in a recess 3¹ so as to be removable and replaceable. It is preferably set vertically of the bowl 1 so that its upper end is adjacent the bowl brim 1².

The type of lighter 5 as illustrated is of the usual fuel magazine type and may be of any desired form, but for manufacturing purposes I prefer the cylindric type as the pocket for this may be a cylindrical bore 4 as by a drill, giving an extinguishing end 4¹ when the blazing lighter is thrust therein. The lighter 5 of the type to which preference is given is provided with a wick W and a friction button 5¹ which is adapted to be struck on the flint 3 to produce the flame indicated in Fig. 1 as F. As shown in Fig. 1 this flame at the moment of being struck is in such a position as to be drawn directly onto the surface of the tobacco T.

In the particular combination shown of the so-called "poker" pipe type, the lighter 5 becomes in the pipe base a stabilizer to assure the position of the pipe on its flat base 1¹. However, the bowl 1 and stem 6 may be of any design and the lighter chamber may be located conveniently according to the general pipe design.

In use the combined pipe and lighter is carried as any ordinary pipe, in or out of case, or in any position in pocket or on smokers' tray.

Upon filling as usual the lighter is simply withdrawn from the pipe and by a simple up-stroke the first burst of flame from the wick W is directly on the surface of the tobacco in the bowl as shown in Fig. 1, with every reasonable chance of an instant light. This is assured by the position of the "flint" 3 or other ignition element 3 which as indicated in Fig. 4 is removable from its recess 3¹ for replacement. As before stated, the element may be variously located but preferably for efficiency and economy should be adjacent the lip or brim of the bowl 1.

Also, the lighter may be variously constituted and variously struck. It is, however, of a type frictioning at the igniter point.

All these matters of design and use may

be varied, but are all contemplated as within the disclosure above given.

What I therefore claim and desire to secure by Letters Patent is:—

- 5 A smoker's pipe comprising a bowl member having a recess on its rear face adjacent the brim thereof, said bowl having a tobacco chamber, a removable and replaceable ignition member in said recess, said bowl member
- 10 having a thickened base below said chamber, said base having a pocket to receive and hold an ignition device and having an entrance beneath said ignition member, a lighter in said pocket adapted to be withdrawn through said entrance and upwardly across said ignition member whereby to ignite said lighter and thence drawn directly across said tobacco
- 15 chamber.

20 In testimony whereof I affix my signature.
KEMPTON ARTHUR EVELETH.
